UNITED STATES PATENT OFFICE.

LESLIE R. HUFF, OF PHILLIPSBURG, NEW JERSEY, ASSIGNOR TO INGERSOLL-RAND COMPANY, OF JERSEY CITY, NEW JERSEY, A CORPORATION OF NEW JERSEY.

CONSTANT-PRESSURE REGULATOR.

Application filed November 23, 1925. Serial No. 70,878.

This invention relates to pressure regulators, but more particularly to a constant pressure regulator for a motor driven turbo compressor in which discharge pressure from the compressor is utilized for regulating the delivery of power to the motor.

The objects of the invention are to maintain constant discharge pressure from the turbo compressor and to prevent over speed-
10 ing of the motor.

Other objects will be in part obvious and in part pointed out hereinafter.

The invention consists of the combinations of elements, features of construction and arrangement of parts having the general mode of operation substantially as hereinafter described and more particularly pointed out in the appended claims and illustrated in the accompanying drawing.

20 The figure in the drawing is an elevation in section of a constant pressure regulator applied to a turbo compressor.

Referring to the drawing, a turbo compressor A viewed from the steam end is provided with a discharge pipe B and is mounted on a foundation C. A steam pipe D leading from a source of supply is adapted to convey steam to the motor of the turbo compressor and has a valve chest E provided with a reciprocatory valve F for regulating the admission of steam to the motor of the compressor.

A cover G is mounted on a base H to form a chamber J. The cover G may be secured to the base H in any suitable manner, and has formed integrally therewith at its top a cylinder K in which is adapted to reciprocate a regulator piston L, against a face O of which may act pressure fluid, such as oil, admitted into a chamber P by a control valve Q. The upper or outer end of the cylinder K is preferably recessed as at R to receive any oil which may leak past the piston L, and a passage S leading from the recess R to a drain passage T formed in the cover G and the base H provides a path for such leakage oil.

In order to adjust the control valve Q so that a suitable pressure may be maintained within the chamber P at all times to tend to force the piston L outwardly, a compression spring U is arranged to act against the upper end of the valve Q and bears at its upper end against an adjusting spindle V. The adjusting spindle V is preferably in the

form of a screw and has a hand wheel W for manipulating the spindle V to adjust the tension of the spring U for different discharge pressures through the discharge pipe B.

In this instance fluid under pressure, as for instance oil, is conveyed from a suitable source of supply through a pipe X into an annular groove Y formed in the valve casing Z. The annular groove Y encircles the sleeve b which is adapted to receive the valve Q and is provided with a plurality of ports c in constant communication with the groove Y. The valve Q is preferably provided with a hollow bore d which extends partly throughout its length and is adapted to communicate with the ports c in the sleeve b through a plurality of radial ports e.

To provide for the escape of oil in case of excessive pressure against the valve Q, a series of ports f are formed in the sleeve b above the ports c to register with an annular groove g formed in the valve casing Z. A pipe h connected at one end to communicate with the groove g and at its other end with the drain passage T provides a convenient means for carrying off the oil by-passed through the valve Q.

Mounted on the valve casing E is a bracket j which supports a cylinder k. A piston o is arranged to reciprocate within the cylinder k and is provided at its upper end with a rod p slideable through a guide q and secured pivotally at its outer end with a balancing lever r, which lever is pivoted at its other end to a governor lever s mounted pivotally on a link t. A piston rod u in this instance forms a connection between the valve F and the piston o.

Formed integrally with the cylinder k is a valve chest v provided with a ported sleeve w which serves as a guide for a pilot valve x. The pilot valve x is provided in this instance with heads y and z and extends outwardly through the valve chest to connect pivotally with the balancing lever r, preferably intermediate the ends of said balancing lever as at 2. A pair of passages 3 and 4 in this instance lead from the top and bottom ends of the cylinder k to the sleeve w and are controlled by the heads z and y respectively of the valve x. Formed in the sleeve w between the passages 3 and 4 is a port 5 which affords communication be-

2
tween the interior of the sleeve *w* and a chamber 6 having a connection 7 through which pressure fluid, such as oil, may be admitted into said chamber from a source 5 of supply.

In order that any oil which may be admitted into the ends of the cylinder *k* may be readily exhausted therefrom to the drain passage *T*, a port 8 is formed in the sleeve 10 *w* above the passage 3. The port 8 communicates with a passage 9 leading to a port 10 which registers with a port 12 opening into the drain passage *T*.

In accordance with the present invention, 15 a head 13 supported by the cover *G* carries a corrugated collapsible diaphragm or sylphon 14. The sylphon 14 in this instance is provided at its lower end with a movable head 15 to which are secured on opposite 20 sides rods or bolts 16. The bolts 16 extend upwardly into a chamber 17 and are secured to a yoke 18 extending transversely through the chamber 17. Intermediate the bolts 16, a rod 19 is secured at one end to the yoke 18 25 and extends upwardly through a sleeve 20 supported by the cover *G* and through the regulator piston *L* to connect pivotally with an arm 21 pivoted on a bracket 22 and extending beyond the bracket to connect with 30 the link *t*. The rod 19 is preferably secured fixedly to the piston *L* as by means of a nut 23. The bore of the sleeve 20 is preferably 35 of sufficient diameter so that contact between it and the rod 19 will be prevented. 40 The sleeve 20 serves to prevent leakage of oil into the chamber 17 and also to prevent excessive leakage of oil into the interior of the piston *L*.

In the present instance a speed governor 45 24 adapted to be connected to the motor is operatively connected to one end of the governor lever *s*. A pipe 25 connected at one end to the discharge pipe *B* is connected at its other end with the head 13 for conveying 50 discharge pressure fluid from the pipe *B* to the interior of the sylphon 14. In order to prevent lateral movement of the free end of the sylphon 14, a pin 26 is secured to the head 15 and extends slidably into a bore 27 in the bottom of the base *H* whereby said pin is guided.

If desired, a recess 28 may be formed in 55 the top of the piston *o* to receive a spring 29 which will tend to constantly force the piston *o* downwardly. In this way the pressure of the oil admitted into the top of the cylinder *K* will be augmented for closing the valve *F*.

The operation of the device is as follows: 60 Assuming that the compressor is running at normal speed, and that pressure fluid is therefore being exhausted through the discharge pipe *B*, a portion of the pressure fluid will flow through the pipe 25 into the sylphon 14 and acting against the head 15

will tend to move said head downwardly towards the bottom of the base *H*. With the turbo compressor *A* running at normal speed, the pressure of the oil entering the chamber *P* will also have attained its maximum pressure and acting against the bottom of the piston *L* will tend to force the piston upwardly and thus tend to counterbalance the force of the pressure fluid acting against the head 15 of the sylphon 14. 75 During the time that the forces acting against the head 15 of the sylphon and against the piston *L* are equal, the valve *Q* will remain approximately in the position indicated in the drawing, that is, the port *e* 80 will be in registration with the ports *e* so that the piston *L* will be exposed directly to the full line pressure of the oil. If in case the pressure acting against the head 15 of the sylphon is sufficiently great to overcome the pressure acting against the face *O* of the piston *L*, said piston will be moved downwardly displacing some of the oil in the chamber *P*. The oil thus displaced will force the valve *Q* upwardly until the ports *e* 90 register with the ports *f* and a portion of the oil will pass into the drain passage *T* through the pipe *h*.

As the discharge pressure in the pipe *B* 95 increases, the increased pressure acting against the head 15 will force said head downwardly together with the bolts and rods connecting said head with the lever 21. The lever 21 will then be rocked about its 100 pivot and will in consequence rock the governor lever *s* and the balancing lever *r* to raise the pilot valve *x*. As the pilot valve *x* is raised, the passage 3 will be placed in communication with the chamber 6 and oil 105 will flow from said chamber to the top of the cylinder *k*. The oil thus admitted will act against the piston *o* and force said piston downwardly, and thus tending to close the valve *F*. In this way the steam flow to the 110 motor of the turbo compressor *A* will be reduced, as well as the discharge pressure from the compressor. With the decreased discharge pressure in the pipe *B* and therefore in the sylphon 14, the pressure acting against the piston *L* may then be greater 115 than the discharge pressure from the compressor and will force said piston upwardly. Such movement of the piston *L* will move the pilot valve downwardly in the sleeve *w* and establish communication between the chamber 6 and the passage 4. 120 With the pilot valve *x* in this position, oil will flow from the chamber 6 beneath the piston *o* and again open the valve *F*. Movement of the pilot valve *x* towards either of its open positions whereby oil will be admitted into one end of the cylinder *k* will also establish communication between the opposite end of said cylinder and the passages leading to the drain passage *T*, so

125

that any oil in either end of said cylinder may be forced therefrom by the pressure acting against the opposite face of the piston *o*.

- 5   Overspeeding of the motor which drives the compressor is at all times prevented by the governor 24 which, being connected to operate the valve *x*, will at certain speeds of the motor rock the lever *s* and the bal-
10   ancing lever *r* to open the pilot valve *x*, and thus admit oil under pressure into the cylinder *k* as hereinbefore described. The governor 24 also controls the admission of steam to the motor when said motor is first being
15   started and before sufficient discharge pressure is built up to set the sylphon 14 in operation.

I claim:

- 20   1. A pressure regulator for motor driven turbo-compressors, comprising a frame, a corrugated collapsible diaphragm connected at one end to the frame and having a movable head at the other end, guiding means for said movable head, bolts secured to the
25   movable head, a yoke connecting said bolts, an operating rod extending from said yoke

and adapted to be connected to regulating mechanism, and a pressure fluid connection between the discharge of the turbo-compressor and the diaphragm, whereby the dia-
30   phragm is subject to discharge pressure for regulating purposes.

2. A pressure regulator for motor driven turbo-compressors and the like, comprising a base having a chamber therein, a cover for
35   the base, a head supported inside the cover, a corrugated collapsible diaphragm connected at one end to the cover, a movable head at the other end of the diaphragm, a guide pin on said head guided in the base, bolts se-
cured at opposite sides to said movable head, a yoke connecting the rods within the cover, a rod extending from the yoke and adapted to be operatively connected to regulating
40   mechanism, and a pipe connection between the discharge of the turbo-compressor and the inside of the collapsible diaphragm, whereby the diaphragm is subject to discharge pressure for regulating purposes.

In testimony whereof I have signed this 50
specification.
